UNITED STATES PATENT OFFICE.

LOUIS KOSSUTH JOHNSON AND ABBOT AUGUSTUS LOW, OF BROOKLYN,
NEW YORK.

TYPE-SETTING APPARATUS.

SPECIFICATION forming part of Letters Patent No. 599,390, dated February 22, 1898.

Application filed June 11, 1897. Serial No. 640,341. (No model.)

To all whom it may concern:

Be it known that we, LOUIS KOSSUTH JOHNSON and ABBOT AUGUSTUS Low, citizens of the United States, residing in the city of Brooklyn, in the county of Kings and State of New York, have invented certain new and useful Improvements in Type-Setting Apparatus, of which the following is a specification sufficient to enable others skilled in the art to which the invention appertains to make and use the same.

Our improvements relate to apparatus for forwarding types from the lower end of a type-containing channel into position for removal to the compositor's stick by hand, and is adapted to effect the presentation of a single type or a plurality of types arranged to form a word or other prescribed combination of characters.

In its general arrangement and operation our present construction embodies the essential features of prior applications for patents made by us, as Serial No. 616,938, filed December 24, 1896, Serial No. 614,165, filed December 2, 1896, and Serial No. 632,400, filed April 16, 1897, our present improvements being designed mainly to render the apparatus more accurate and delicate in operation.

A distinguishing feature of our present invention consists in the special construction and arrangement of the actuating-lever and gravity-latch, by which the type-forwarding mechanism is controlled, in such manner that the gravity-latch holds the type-bearing finger out of the way of the advancing type during the forward movement of the type-forwarding blade. We accomplish this by arranging the fulcrum of the actuating-lever so that the forward end of the latter tends constantly to descend and in forming a shoulder upon the gravity-latch, which engages with the stationary cross-bar against which the gravity-latch rests, thereby sustaining the type-finger in position to receive the advancing types without impeding their progress. Incidentally in this connection our invention includes means for adjusting this shoulder or rest longitudinally upon the gravity-latch for the purpose of setting the parts accurately with relation to each other and to the types to be handled. In fact, variations in the number of types to be removed simultaneously

may thus be compensated for without disturbing the pusher-finger, which has heretofore been made adjustable for this purpose.

Another feature of our invention relating to the trigger or releasing-lever consists in the formation of the latter at its forward end with a socket-post in connection with the use of an adjustable screw-post, to which the finger-piece is swiveled, so that the finger-piece, resting between the vertical lateral type-guards on the holder, may be raised or lowered with relation to the path of the pusher without rotation by simply turning the screw-post in one direction or the other, as the case may be.

Another distinguishing feature of our invention consists in a rotatable bearing-surface for the upper side of the forwarded type, arranged in conjunction with a stationary heel-bearing and lateral supports for the type, substantially as hereinafter set forth, whereby the frictional resistance to the withdrawal of the types is reduced to the minimum.

Our invention also includes the special construction of a channel-holder for pressing the channel against the inner supporting-wall of the holder, so as to insure the proper alignment of the channel with relation to the type-forwarding blade, the path of which is at one side of the channel.

In the accompanying drawings, Figure 1 is a front elevation of a series of our improved type-forwarding devices arranged side by side and illustrating their use in conjunction with each other in the form of a compositor's type-case. Fig. 2 is a sectional elevation showing the parts at rest. Fig. 3 is a similar view showing the parts immediately after the withdrawal of the types last forwarded. Fig. 4 is a similar view showing the parts when the type-forwarding blade is fully retracted. Fig. 5 is a similar view showing the parts during the forward movement of the type-blade. Figs. 6 and 7 are elevations of opposite sides of the channel-holder. Figs. 8 and 9 are front and rear elevations of the channel-holder; Fig. 10, a plan thereof. Fig. 11 is a detail view of the finger-piece. Fig. 12 is a horizontal section illustrating the relation of the pusher-blade to the lower end of the type channel and holder; Fig. 13, a hori-

zontal section upon plane of line 13 13, Fig. 5; Fig. 14, a plan of the forward end of the type-lever. Figs. 15 and 16 are respectively a side elevation and a plan of the pusher.

5 In the drawings, A represents a stationary frame of the apparatus, of which the table *a* is a part. This table *a* is formed with sockets *a'* for the reception of the tenons *h* of the channel-holders *H*, as heretofore.

10 Each type-containing channel *C* is formed at its lower end with a horizontal type-supporting shoulder *c* on one side of the vertical slot *c'*, made in the path of the pusher-blade *p*, which path extends between said horizontal shoulder *c* and the opposed wall of the channel *C*.

The type-channel *C* is supported by and upon the slide *S*. This slide *S* fits into a vertical groove *h'*, formed in the side of the holder

20 *H*, and is made adjustable vertically by suitable means, as by the vertical set-screw *s*, engaging with a female screw-thread formed in the lower part of the holder, as shown in the drawings, which construction is preferable in that the sides of the holder are left free and unobstructed, while the adjustment of the slide can be readily effected when the holder *H* is removed from the table *A*. It is to be understood that this adjustment of the 25 slide *S* is for the purpose of regulating the position of the type-shoulder *c* upon the channel *C* with relation to the position of the pusher-blade *p*, the path of which is prescribed.

The channel is held in a vertical position 30 by the wall *h³* of the holder upon one side and by the lateral arm *W* on the other. In our last application hereinbefore referred to this lateral arm *W* was pivotally supported on the rear of the holder *H* and tended constantly 35 to press against the side of the channel by reason of the action of a spring *w*, so as to compensate for differences in thickness of the channels which might be used in the holder and to insure the alinement of the 40 channel with relation to the pusher-blade *p*. In our present application we accomplish the same result in a more simple manner by making the lateral arm *W* itself sufficiently 45 elastic to yield to allow the insertion of the channel, while thereafter tending to retain the channel constantly and rigidly in the required position.

The front guard *h⁴* of the holder is formed 50 at its lower end with the stationary type-heel *g*, which acts in conjunction with the finger-piece *f* below substantially in the manner set forth in our prior applications referred to. In the present case the lower end of the front guard *h⁴* is also bifurcated to form the cheek-pieces *h⁵*, between which is pivotally supported 55 the roller-bearing *h⁶* above the position of the upper end of the finger-piece *f*. The cheek-pieces support the types laterally, while the roller *h⁶* reduces the frictional 60 resistance to the withdrawal of the types.

65 *P* is the reciprocating pusher-bar, to which the pusher-blade *p* is attached. The pusher-

blade *p* is connected to the eccentric *E* by the pitman *F* and eccentric-strap. The eccentric *E* is loose upon the power-shaft *I*, except 70 when coupled thereto by the pawl *e*, which engages with the shoulder *i* on said shaft when not held out of engagement therewith by the upper end of the gravity-latch *J* on the inner end of the actuating-lever *L*. The 75 shaft *I* is in constant rotation, so that directly the pawl *e* is released it encounters and engages with the shoulder *i*, and thereby carries the eccentric *E* around with the shaft until the pawl *e* is again released, which occurs at the end of a single rotation, provided 80 the type has been forwarded between the upper heel-guard *g* and the type-finger *f*, in which position the type holds the actuating-lever *L* in such relation to the stationary bar 85 *R* that the gravity-latch *J* tilts backward with its upper end in the path of the outer end of the pawl.

The protruding and retracting of the upper 90 end of the gravity-latch *J* is effected by reason of the contact of its inclined surface *j* with the stationary bar *R* or its equivalent, the lower end of said latch *J* being pivoted to the actuating-lever *L* in such position that such inclined surface is held by gravity in 95 constant engagement with said stationary bar *R*. The upward thrust of the gravity-latch *J* is limited by the shoulder *j'* thereon, which thus also limits the downward movement of the finger-piece *f*. 100

In order to attain the greatest delicacy and accuracy in all the parts, as well as to compensate for variations in the size or number of types to be removed simultaneously, this shoulder *j'* upon the gravity-lever *J* is made 105 adjustable longitudinally thereon by any suitable means. As shown in the drawings, the shoulder *j'* forms part of a plate *j²*, which is secured to the gravity-latch *J* by set-screws *j³*, passing through longitudinal slots *j⁴*, by 110 which the distance between the said shoulder *j'* and the pivot of the gravity-latch may be varied or adjusted with accuracy to meet the requirements of actual use.

The finger-piece *f* is mounted upon the 115 front end of the actuating-lever *L*, which latter is so pivoted that its forward end tends constantly to move downward, which movement is limited by the stationary bar *R*, as aforesaid. The front end of the actuating- 120 lever is formed with a socket-post *l*, the upper portion of which is formed with an internal screw-thread *l'*, which engages with the male screw-thread *f'* on the portion of the shank or screw-post *f²* which supports the finger-piece *f* proper. The finger-piece *f* is swiveled 125 to the screw post or stem *f²* or otherwise so connected therewith that the shank *f³* is free to turn independent of the finger-piece *f*, the flat upper end of which rests between the 130 cheeks *h⁵*, which prevent it from turning laterally on its axis. Thus in the drawings the upper end of the stem *f²* has a small annular groove *f⁴* turned in it, while the lower end of

the finger-piece f fits over this grooved end of the shank and is coupled thereto by a small screw or pin f^5 , projecting into the groove f^4 , but in no wise interfering with the rotation of the stem f^2 .

When it is desired to adjust the finger-piece with relation to the thickness of type or to the number to be withdrawn simultaneously, the set-screw l^2 is loosened and the finger-piece f is raised or lowered by turning the shank f^2 in one direction or the other, as the case may be, when the set-screw l^2 is again adjusted to secure the parts in their new position. By the use of the threaded shank f^2 , turning in the threaded socket-post l , we are enabled to attain a very delicate and accurate adjustment of the finger-piece f with relation to the roller h^6 and type-heel g .

What we claim as our invention, and desire to secure by Letters Patent, is—

1. In a compositor's type-case the combination of a type-forwarding blade having a prescribed path of reciprocation, mechanism for actuating said reciprocating blade, a trigger-lever for controlling said actuating mechanism, said actuating-lever being formed with a finger-piece for contact with the type, and a gravity-latch mounted upon the other end of said lever and acting in conjunction with a stationary cross-bar, said gravity-latch being formed with a shoulder for limiting the movement of the lever, substantially in the manner and for the purpose described.

2. The combination with the type-containing channel, channel-holder, type-forwarding blade and reciprocating mechanism of an actuating-lever formed with a finger-piece controlled by the type and a gravity-latch formed with an inclined surface, and lateral shoulder for engaging with a stationary cross-bar, for the purpose and substantially in the manner described.

3. The combination with the type-containing channel, channel-holder, type-forwarding blade and reciprocating mechanism of an actuating-lever formed with a finger-piece controlled by the type and a gravity-latch formed with an inclined surface and a lateral shoulder which is adjustable with relation to the stationary cross-bar for the purpose and substantially in the manner described.

4. The combination of a type-containing channel, channel-holder, supporting-table, reciprocating type-blade, mechanism for actuating said reciprocating type-blade, a trigger-lever having a finger-piece controlled by the type, and a gravity-latch J , formed with the inclined surface j , and the adjustable plate j^2 , having the lateral shoulder j' , for engagement with the stationary cross-bar, sub-

stantially in the manner and for the purpose described.

5. In a compositor's type-case, substantially such as described the combination with a type-containing channel, of a channel-holder 65 formed with a flexible side wall for the purpose and substantially in the manner described.

6. The combination with a type-containing channel, type-holder, type-pusher blade, 70 mechanism for reciprocating the same, and a trigger-lever having the gravity-latch for controlling the actuating mechanism, of a finger-piece for bearing upon the under side of the type, said finger-piece being swiveled to a 75 shank which is adjustable upon the end of the trigger-lever, substantially in the manner and for the purpose described.

7. In combination with the type-channel, channel-holder, type-forwarding blade and 80 actuating mechanism, the trigger-lever provided with the gravity-latch acting in conjunction with a stationary cross-bar to control the actuating mechanism, and the finger-piece f , swiveled to the upper end of a screw- 85 post formed with a screw-thread engaging with a socket-post on the front end of the actuating-lever, substantially in the manner and for the purpose described.

8. In combination with the type-channel, 90 channel-holder, type-forwarding blade and actuating mechanism, and with the trigger-lever and its gravity-latch, of the finger-piece f , screw-post f^2 , formed with the screw-thread f^1 , and the socket-post l , formed with the female screw-thread for engagement with the shank f^2 , and provided with a set or lock screw l' , substantially in the manner and for 95 the purpose set forth.

9. The combination with a type-containing channel, channel-holder, type-forwarding blade, actuating mechanism, trigger-lever and finger-piece, of a front guard for the type provided with a roller-bearing for the upper side of the type, substantially in the manner 105 and for the purpose described.

10. In combination with the type-containing channel, channel-holder, type-forwarding blade, actuating mechanism, trigger-lever and finger-piece, of the front guard for the 110 type formed with the lateral type-guards having a bearing-roller mounted between them for the purpose and substantially in the manner described.
